UNITED STATES PATENT OFFICE.

THOMAS S. GORRELL AND EDWARD M. TUBBS, OF PITTSBURG, KANSAS.

HAY-PRESS.

SPECIFICATION forming part of Letters Patent No. 381,007, dated April 10, 1888.

Application filed December 20, 1887. Serial No. 255,522. (No model.)

To all whom it may concern:

Be it known that we, THOMAS S. GORRELL and EDWARD M. TUBBS, citizens of the United States, residing at Pittsburg, in the county of 5 Crawford and State of Kansas, have invented new and useful Improvements in Hay-Presses, of which the following is a specification.

Our invention relates to improvements in hay-presses; and it consists in certain novel 10 features hereinafter described and claimed.

In the accompanying drawings, which fully illustrate our invention, Figure 1 is a longitudinal section of our improved press. Fig. 2 is a plan view of the same. Fig. 3 is a detail 15 view of the plunger, and Fig. 4 is an end view.

Referring to the drawings particularly by letter, A designates the press-box, which is constructed in the usual manner, with the 20 longitudinal beams B, the top C, having a feed-opening, D, the bottom G, and the sides E. The press-box is further provided with the vertical posts, standards, or braces F on its sides, as shown. The longitudinal beams 25 are extended past the sides at one end, and at this end cross-beams H are secured between the beams. To the sides of these cross-beams we bolt the journal-boxes I, in which the ends of the fulcrum bolt or pin J have bearings. 30 The sweep or operating-lever K is fulcrumed on this bolt or pin J, and the said bolt or pin passes through the top of the press, a brace, L, extending from the upper end thereof to the sweep, as shown, to steady the movement 35 of the same. To the upper and lower sides of the sweep, at the inner end of the same, we secure the arms or plates M, which pass around the fulcrum-pin and project inward beyond the inner end of the sweep.

40 N designates a pitman having its opposite ends pivoted, respectively, between the inner ends of the arms M and between the lugs O on the outer end of the plunger P. This pitman N is composed of the sockets Q, through 45 which the pivot-pins are passed, and which are provided with the lateral projections R, and the rod S, having its ends fitted in the said sockets. In order that the rod S may be firmly held in the sockets, we provide the 50 longitudinal fastening-bars T, which are arranged parallel with the rod S, on opposite sides of the same, and have their opposite ends

secured rigidly to the lateral projections R of the sockets.

The plunger P is provided on its opposite 55 sides with the outwardly-extended guide-rails U, which steady the motion of the plunger and serve to maintain said motion in a direct longitudinal line by bearing against the sides of the press.

Secured to the opposite sides of the press and to the posts are the stop-bars V. These 60 stop bars are secured at such a height as to be in the same horizontal plane as the sweep, and they project outward and toward the rear 65 end of the press, so as to limit the movement of the sweep to the necessary degree by reason of the sweep contacting with the ends of the bars, as will be readily understood.

In practice the hay is fed into the press in 70 the usual manner and the plunger forced thereagainst to compress it by moving the sweep. The sweep is allowed one-half of a complete revolution, so that during each 75 stroke it will force the plunger in against the hay, compressing the same, and then withdraw it, leaving room for another quantity of hay.

It will be seen at once that our press is very 80 simple, and our improved construction is such 85 that the parts will be considerably strengthened, permitting the application of great power.

Having thus described our invention, what we claim, and desire to secure by Letters Patent, is—

The combination of the press-box, the plunger, the sweep provided with the arms M on its upper and lower sides, the sockets Q, pivoted to the plunger and between the arms 90 M and having the projections R, the rod S, having its ends fitted in said sockets, and the securing-rods arranged parallel with said rod S and having their ends secured rigidly to the projections R, substantially as set forth. 95

In testimony that we claim the foregoing as our own we have hereto affixed our signatures in presence of two witnesses.

THOMAS S. GORRELL.
EDWARD M. TUBBS.

Witnesses:

JOE McLAUGHLIN,
JOE DORID.
